UNITED STATES PATENT OFFICE.

EARL H. SHANK, OF TERRA ALTA, WEST VIRGINIA.

CABINET POLISH.

1,411,193.

Specification of Letters Patent. Patented Mar. 28, 1922.

No Drawing.

Application filed August 4, 1921. Serial No. 489,850.

To all whom it may concern:

Be it known that I, EARL H. SHANK, a citizen of the United States, residing at Terra Alta, in the county of Preston and State of West Virginia, have invented certain new and useful Improvements in a Cabinet Polish; and I do hereby declare the following to be a full, clear, and exact description of the invention, such as will enable others skilled in the art to which it appertains to make and use the same.

The object of the invention is to provide a polishing preparation or composition of matter suitable for vehicle bodies, furniture and like surfaces of wooden structures and others having a hard smooth finish, and particularly to provide a preparation having a cleansing and grease cutting and neutralizing quality which will have the effect of polishing or producing a lustre by accretion and reinforcement or addition rather than by attrition or reduction and which therefore is cumulative by repeated use in its beneficial effect upon the surface treated thereby, and serves to supplement previously varnished, coated and polished surfaces to prolong the attractive appearance thereof and indefinitely defer the necessity for repainting and varnishing, particularly in reference to automobile bodies.

While minor variations in the relative

proportions of the ingredients and within the range of equivalence in the ingredients themselves may be resorted to, particularly when the determination as to equivalence is based upon the similarity of chemical effect and relation by reaction to other ingredients, the formula which has been found in practice to be effective for the purpose and which therefore may be regarded as preferable in substantial particulars consists of equal parts by volume of clear varnish, turpentine, raw linseed oil, kerosene, gasoline.

These items should be thoroughly mixed or ground together to produce a homogeneous composition which at normal or mean temperature is sufficiently fluid to be applied either with a brush, sponge or cloth after the thorough cleansing of the surface by ordinary washing means.

Having thus described the invention, what I claim is:

The herein-described composition of matter for use as a polish which consists of varnish, turpentine, linseed oil, kerosene and gasoline.

In testimony whereof I affix my signature in presence of a witness.

EARL H. SHANK.

Witness:

BENNETT S. JONES.
